UNITED STATES PATENT OFFICE.

ANNA J. SCHLUNKE, OF FARGO, NORTH DAKOTA.

GRAIN SEPARATOR.

Application filed September 2, 1921. Serial No. 497,923.

To all whom it may concern:

Be it known that ANNA J. SCHLUNKE, a citizen of the United States of America, residing at Fargo, in the county of Cass and 5 State of North Dakota, has invented a new and useful Grain Separator, of which the following is a specification.

The purpose of the present invention is to provide a separator, particularly a screen, 10 riddle or sieve for separating various grains, particularly oats and wheat, or longer grain and shorter grain.

Another purpose is to provide a separator of this general character, wherein a riddle, 15 screen or sieve is provided having rows of diamond shaped raised protuberances and openings, disposed in rows, the openings being disposed between the raised protuberances in rows in one direction, while the 20 openings of one row are in staggered relation with those of an adjacent row, and in staggered relation to the protuberances, and the protuberances of one row of protuberances, so that the long grain will be guided 25 past the openings.

It will be noted that the protuberances are diamond shaped, and owing to their staggered relation, they cause to be formed diagonal intersecting channels, wherein the 30 openings are located in staggered relation, thereby guiding the long grain past the openings, while shorter grain falls through the openings. Furthermore the protuberances are beveled, though they may be otherwise 35 constructed, and otherwise shaped, to further facilitate the guiding of the grain.

It has been found that by varying the size of the protuberances, and their location, as well as the size and location of the openings, that grain or seed of various sizes and 40 kinds may be separated, it being obvious that to accomplish this, it will be only necessary to resort to variations in the screen or sieve.

Furthermore it is obvious that the combination of two or more of the screens, sieves 45 or riddles may be employed, to effectively separate long and short seed or grain, in fact the device may be used for separating all kinds of grain.

While the design and construction at present illustrated and set forth are deemed preferable, it is obvious that as a result of 50 a reduction of the invention to a more practical form for commercial purposes, the invention may be susceptible of changes, and

the right to these changes is claimed, provided they are comprehended within the scope of what is claimed.

The invention comprises further features and combination of parts, as will be herein-after set forth, shown in the drawings and claimed.

In the drawings:—

Figure 1 is a vertical longitudinal sectional view through a separator constructed 65 in accordance with the invention, showing the riddle or sieve in position;

Figure 2 is a sectional view on line 2—2 of Figure 1, showing the sieve, screen or riddle in plan view;

Figure 3 is a sectional view on line 3—3 of Figure 2; and

Figure 4 is an enlarged detail perspective view of a portion of the riddle, screen or 75 sieve.

Referring to the drawings, 1 designates the separator in its entirety, broadly showing a construction generally used, and provided at one end thereof with a hopper 2. In the outlet mouth of this hopper is a revoluble feed roll 3, to which any suitable power may be operatively connected for turning the feed. The feed is in the nature of a rectangular strip, preferably provided with extending corners. At the outlet mouth 85 of the hopper 2 is arranged a directing spout 4 having an inner outlet 5 directed inward of the separator and being disposed a considerable distance above a pan 6. In the separator is arranged a fan casing 7 having 90 a revoluble fan 8 therein, the casing being provided with an outlet spout that is disposed at a downward angle and which is arranged over the pan 6. The spout is indicated by the numeral 9.

Below the pan 6 is an angularly arranged sieve, riddle or screen 10, and to the rear of the sieve or riddle is an angularly disposed deflector plate 11.

The deflector plate 11 is arranged at an 100 outward angle, while the riddle or sieve 10 is arranged at a downward angle. The deflector 11 is positioned only a slight distance from the pan 6, and as the wheat or other grain is fed from the hopper and is delivered on the pan 6 through the spout 5, the blast of air from the fan 8 through the spout 9 will bring the light foreign matter, such as king head, etc., over the pan into 105 contact with the inner deflector 11, and from 110

thence out of the separator, the wheat grain being delivered from the pan onto the sieve or riddle 10.

The riddle, sieve or screen 10 is constructed of any suitable material preferably sheet metal of the required thickness and size, and is provided with an upstanding flange 12 at one end, and formed throughout its area is a plurality of protuberances 13. These protuberances are preferably diamond shaped, though they may be otherwise formed, and are constructed by pressing or punching them upwardly from the material. The protuberances have beveled side walls 14, and owing to the protuberances being staggered, the beveled or inclined walls are in alignment, thereby providing diagonal intersecting channels 15, which act to guide the grain in intersecting diagonal directions. The riddle, sieve or screen is provided with a plurality of rows of openings 16, which are in staggered relation, and are formed in the channels 15, so that when the grain is guided in diagonal intersecting directions it will be directed toward the openings through which the smaller grain will pass, while the larger grain will continue on its passage through the channels in diagonal intersecting directions. Obviously the openings of one row are alternately arranged with the protuberances in the same row and in staggered relation with the protuberances of an adjacent row, as well as in staggered relation to the openings of an adjacent row. It is obvious that the openings and the protuberances may be arranged in various positions, and increase or decrease in size, as the case may be, or as found convenient, for separating various grain. Furthermore the combination of more than two riddles or sieves may be employed, to facilitate the separation of various grains, large or small, or the separation of oats, wheat, barley, rye, mustard and flax seed and the like, it depending entirely upon the construction or character of screen or riddle.

The invention having been set forth, what is claimed as being useful is:

1. A riddle for grain separators formed on its top surface with a plurality of protuberances defining intersecting channels the side walls of said protuberances converging in a direction opposite to that in which the grain

travels to deflect the grain in different directions and thereby cause its promiscuous movement through the several channels, the riddle further being formed with a plurality of openings disposed in the bottoms of the channels. 55

2. A riddle for grain separators formed on its top surface with a plurality of protuberances defining intersecting channels, the side walls of said protuberances converging in a direction opposite to that in which the grain travels to deflect the grain 60 in different directions and thereby cause its promiscuous movement through the several channels, the riddle being further formed with a plurality of openings formed in the bottoms of the channels at the points of intersection thereof. 70

3. A riddle for the purpose indicated comprising a plate having a plurality of protuberances formed on its top face, said protuberances being polygonal in plan and arranged to provide a plurality of intersecting channels, the corners of said protuberances being disposed to engage the grain precipitated on said riddle and direct it promiscuously through the several channels, 75 80 openings being formed in the bottoms of the channels opposite the corners of said protuberances.

4. The combination with a grain separator having a feed plate, of a sieve or riddle 85 disposed below and spaced from said plate, said sieve or riddle comprising a body having a plurality of rows of protuberances, the protuberances of one row being in staggered relation with those of an adjacent 90 row and being diamond shape and having bevelled walls, which are in diagonal alignment, thereby causing to be formed diagonal intersecting channels, said body having a plurality of rows of openings formed in the 95 bottoms of the channels, toward which the grain is guided by the walls of the protuberances.

In witness whereof, in the presence of two witnesses, the inventor's signature is 100 hereunto affixed.

ANNA J. SCHLUNKE.
